CLAIM

The ornamental design for an outsole, as shown and described.

DESCRIPTION

FIG. 1 is a bottom plan view of an outsole according to my new design;

FIG. 2 is a right side elevational view thereof;

FIG. 3 is a front elevational view thereof;

FIG. 4 is a left side elevational view thereof;

FIG. 5 is a rear elevational view thereof;

FIG. 6 is a sectional view taken on line 6—6 of FIG. 1;

FIG. 7 is a sectional view taken on line 7—7 of FIG. 1;

FIG. 8 is a sectional view taken on line 8—8 of FIG. 1;

FIG. 9 is a sectional view taken on line 9—9 of FIG. 1; and,

FIG. 10 is a sectional view taken on line 10—10 of FIG. 1.

The dashed lines are for environmental purposes only and form no part of this design.
